WIRE CONTAINER

Robert P. Messenger, Kenilworth, and Lee H. Kaupke and Russell R. Raney, La Grange, Ill., assignors to International Harvester Company, a corporation of New Jersey

Application August 26, 1944, Serial No. 551,344

8 Claims. (Cl. 242—129)

This invention relates to a new and improved wire container and is especially adapted for use on a wire tying hay baling machine.

An important object of the present invention is to provide a wire container from which a strand of wire may be continuously extracted without tangling or becoming snarled so as to hinder continuous tying of bales.

Another important object of this invention is the provision of means for providing an open top wire container which is constructed in such a manner that rain or other precipitation is prevented from entering the chamber containing the coil of wire to be used in tying bales.

Another and still further important object of the present invention is to provide a wire container wherein a coiled wire is submerged in oil to prevent rusting and to facilitate easy removal of a single strand of the coil of wire.

A still further important object of this invention is to provide a wire container and wire removal means which consists of a plurality of concentric circular elements.

Other and further important objects will become apparent from the disclosures in the following specification and accompanying drawing in which:

Fig. 1 is a top plan view of the wire container of this invention; and

Fig. 2 is a sectional view of the wire container taken on the line 2—2 of Fig. 1.

As shown in the drawing:

The reference numeral 10 indicates generally a U-shaped or trough-like circular receptacle adapted to receive a coil of wire designated by the numeral 11. The receptacle 10 is liquid-tight, and as will be readily seen the coil of wire 11 is covered with an oil 12 to prevent rusting or other erosion of the wire and also to contribute to the easy removal of the end strand 13 of the coil of wire 11.

The inner circumference 14 of the U-shaped container 10 is inclined inwardly at its upper end. The outer circumference 15 of the U-shaped receptacle or container 10 forms a vertical wall at right angles to the base 16 of the container 10.

A centrally positioned frusto-conical member 17 has its lower small diameter end flared outwardly as shown at 18. The outwardly flared rim 18 of the member 17 is adapted to partially telescope the inner inclined wall 14 of the wire container 10 and is welded thereto to form a rigid construction. The upper peripheral circular edge or the large diameter end of the member 17 is rolled, as shown at 19, so that it presents a smooth

curved surface over which the strand of wire 13 may freely pass.

A top portion of the container 20 includes a cylindrical member 21 which is adapted to snugly engage by means of a partial telescoping of the outer wall 15 of the base or container member 10. The lower edge of the cylindrical member 21 is rolled outwardly, as shown at 22, and this circular rolled edge 22 is adapted to rest on a ledge 23 formed by intermittent outward projections of the wall 15. These projections 23 may consist of any number around the periphery of the wall 15, but it would be sufficient if there were only two at diametrically opposed points in order to limit the extent of the telescoping of the member 21 over the wall 15. These two cylindrical members 15 and 21 are securely fastened together by means of bolts 24 which are adapted to pass outwardly through holes in the cylindrical wall 15 and to extend through slots 25 in the lower edges of the cylindrical member 21. Wing nuts 26 are manually screwed on to the bolts 24 and are so fixed that they compress spacers 27 against the surface of the cylindrical wall 21, whereby the cylindrical members 15 and 21 are securely fastened to each other. The upper portion 20 of the container is easily removed from the base or container portion 10 by simply loosening the wing nuts 26 and vertically lifting the upper member 20 from the lower member 10. This lifting is permitted because of the slots 25 in the cylindrical portion 21 of the upper member 20.

This upper member 20 further includes a frusto-conical hood 28 which may be formed integrally with the cylindrical portion 21 or may be welded or otherwise attached to the cylindrical member 21, as shown at 29. The upper rolled edge 30 of the conical member 28 has a circumference of less magnitude than the circumference of the rolled rim 19 of the inner cone 17. This feature prohibits rain or snow, falling vertically, from entering the wire chamber 10. If rain were permitted to contact the coil of wire 11, it would undoubtedly cause rusting and might possibly damage the wire to such an extent that it could not be used. This particular construction which prevents rain from reaching the wire chamber permits visual inspection of the wire extruded from the container, whereas a simple cover would prevent the operator of the baler or other machine, wherein wire is used, from watching the removal and hence he would be unable to know whether the wire was kinked or tangled.

A restricted circular guide 31 is positioned centrally of the entire container so that it is con-

centric with the container 10 and also the rolled edges 19 and 30. This guide 31 includes a central aperture 32 and an outwardly rolled flange 33. As shown in the drawing, the guide 31 is supported by three brackets 34 spaced at intervals of 120°. It must, of course, be realized that this guide 31 may be supported in any suitable manner and by any number of brackets. The brackets 34 are welded or otherwise fastened to the inner surface of the cone 17 at 35 and at their other ends are attached to ribs 36 within the guide 31 by means of rivets 37 or the like.

The strand of wire 13, taken from the coil of wire 11, proceeds upwardly through the space between the rolled rims 19 and 30; riding or sliding over the large roll 19 and thereupon proceeds radially inwardly over the curved flange 33 of the guide 31, and thence downwardly through the central aperture 32 of the guide.

The construction shown and described is conducive to easy wire removal from a coil of wire with the chances of the wire becoming tangled reduced to a minimum.

What is claimed is:

1. A wire container adapted to permit withdrawal of a single strand of wire, comprising a circular receptacle U-shaped in cross-section for holding a coil of wire, an upstanding member supported by the inner periphery of the U-shaped receptacle having a circular upper rim, and a central guide supported within and adjacent the upper edge of said circular rim, said central guide having a downwardly and inwardly curved flange conducive to easy passage of a strand of wire.

2. A wire container comprising a circular trough receptacle for holding a coil of wire, a frusto-conical member supported by the inner wall of the receptacle and extending upwardly and outwardly and terminating in a circular rolled rim, and means associated with the outer wall of said receptacle for cooperating with said frusto-conical member to prevent rain from entering said trough receptacle and whereby a single strand of the top of said coil of wire may be withdrawn from the receptacle over said rolled rim.

3. A wire container comprising a circular trough receptacle, a coil of wire in said receptacle, an inner frusto-conical member supported by the inner wall of the receptacle and extending upwardly and outwardly and an outer frusto-conical member supported by the outer wall of the receptacle and extending upwardly and inwardly so that the upper circular edge of the outer frusto-conical member vertically covers the upper circular edge of the inner frusto-conical member, whereby rain is precluded from vertically entering the receptacle.

4. A wire container comprising a circular trough receptacle, a coil of wire in said receptacle, an inner frusto-conical member supported by the inner wall of the receptacle and extending

upwardly and outwardly and an outer frusto-conical member supported by the outer wall of the receptacle and extending upwardly and inwardly so that the upper circular edge of the outer frusto-conical member vertically covers the upper circular edge of the inner frusto-conical member, and an inner central guide supported within the inner frusto-conical member whereby a strand of wire from the coil is carried upwardly over the circular edge of the inner frusto-conical member and thence downwardly through the central guide.

5. A wire container including an open top circular trough receptacle for a coil of wire submerged in a lubricant, an inner frusto-conical member attached to said receptacle and extending upwardly and outwardly and terminating in a circular rolled edge, an outer frusto-conical member attached to said receptacle and extending upwardly and inwardly and terminating above and in a smaller diameter circular rolled edge than the circular edge of the inner frusto-conical member.

6. A wire container including an open top circular trough receptacle for a coil of wire submerged in a lubricant, an inner frusto-conical member attached to said receptacle and extending upwardly and outwardly and terminating in a circular rolled edge, an outer frusto-conical member attached to said receptacle and extending upwardly and inwardly and terminating above and in a smaller diameter circular rolled edge than the circular edge of the inner frusto-conical member, and a central guide member having a curved flange with a central aperture whereby a single strand of the coil of wire proceeds upwardly between the rolled edges of the frusto-conical members, over the curved flange of the guide member and thence downwardly through the aperture.

7. A wire container comprising a substantially circular receptacle providing an annular chamber to house a coil of wire, the chamber formed by annular walls relatively inclined to form a narrow annular guide throat for a strand of wire being withdrawn from the annular chamber, said receptacle being axially hollow and open at its opposite ends, an axially disposed annular guide carried by the inner wall of the chamber in the axial hollow portion of the receptacle so that the strand of wire reeled from the guide throat passes over the annular guide and then axially therethrough and through said axial hollow portion of the receptacle.

8. A wire container as in claim 7 in which the annular chamber is liquid tight to carry a rust-inhibiting liquid in which the coil of wire is immersed.
